William J. Myrick

UNITED STATES PATENT OFFICE.

WILLIAM J. MYRICK, OF BINGHAMTON, NEW YORK.

IMPROVEMENT IN CUPBOARD-CATCHES.

Specification forming part of Letters Patent No. **147,515**, dated February 17, 1874; application filed October 20, 1873.

To all whom it may concern:

Be it known that I, WILLIAM J. MYRICK, of the city of Binghamton, State of New York, have invented a Closet-Door Catch, of which the following is a specification:

The object of this invention is to furnish a good and efficient door-catch for closet, book-case, or other doors, that will readily hold the door to its place when closed.

Figure 1 shows a front view of the cap *a* to the catch, it being fastened to the face of the door by screws, *A*. *B* being the line of the joint between the door and the jamb, the cap *a* serving as a handle with which to open the door.

Fig. 2 shows a section on the line *X Y* of Fig. 1, having the wood-work of the door removed, thus showing the catch *c* and its case *b*, attached to the door-jamb by screws. The catch *c* is held to its place in the case *b* by the pin *f*, allowing *c* to work up and down readily.

Fig. 3 is a top view, showing the catch in dotted lines, *d* being the door, and *e* the jamb.

The dotted lines show concealed parts.

The door being pushed shut, the catch *c* is

thrown up; and when the door is fully to its place, the catch *c* drops, and the door is held by the barb on the catch taking hold of the plate *a'* on the lower part of the cap *a*, which plate extends up under the projecting portion of the cap *a*. The catch *c* is double-barbed, so that it may be used either on a right or left hand door.

In opening the door, the fingers are thrust up under the cap *a*, and, striking against the catch *c*, it is thrown up until it no longer retains a hold on the plate *a'*; when the door may readily be drawn open by means of the cap *a*.

I claim as my invention—

The double-barbed reversible catch *c*, attached to the door-jamb, in combination with the cap *a* and its plate *a'*, secured to the door, substantially as and for the purpose set forth.

WILLIAM J. MYRICK.
